UNITED STATES PATENT OFFICE.

CHARLES O. BAXTER, OF ST. LOUIS, MISSOURI.

SIGN.

SPECIFICATION forming part of Letters Patent No. 352,030, dated November 2, 1886.

Application filed August 26, 1884. Serial No. 141,516. (No model.)

To all whom it may concern:

Be it known that I, CHARLES O. BAXTER, of the city of St. Louis, in the State of Missouri, have invented a certain new and useful Improvement in Signs, of which the following is a full, clear, and exact description, reference being had to the accompanying drawings, forming part of this specification, and in which—

Figure 1 is a side or face view. Fig. 2 is a transverse section taken on line 2 2, Fig. 1.

My invention relates to a small hanging sign; and it consists in a body of wood having composition faces with advertising letters or words cast integral therewith and in relief, as more fully described hereinafter.

In Letters Patent No. 306,462, issued October 14, 1884, I claim an advertising-picture or show-card frame having descriptive letters or words and ornamental or fanciful designs, said letters or words and designs being cast integral with the substance of the face of the frame. It is such a face as this which I have applied to a sign.

Referring to the drawings, A represents the body made of wood-veneers with their grains crossed, as shown in Fig. 2, to prevent warping. The body A consists of a rear or central piece, a, having rounded edges a', and outer pieces, a'', having their edges a'' rounded toward the edges of the central piece.

The body may have eye-screws B, by means of which the sign can be suspended from a suitable object. The body has a plate or face, C, on one or both sides, preferably on both, con-

sisting of a suitable composition with words 35 cast integral therewith in relief, as shown in Fig. 2.

This sign is intended to be hung up in dry places—as, for instance, in stores—to advertise different articles. It is very cheaply produced, 40 and has a fine and strong appearance when finished up in different shades and colors.

I claim as my invention—

1. A sign consisting of a wooden body, A, formed with rear piece, a, having rounded 45 edges a', and outer piece, a'', having rounded edges a'', and a plate, C, having ornamental or fanciful designs cast integral with the plate, the grain of the pieces being crossed, substantially as described.

2. A sign consisting of a wooden body, A, having central piece, a, and outer pieces, a'' a'', and plates C C, each plate having ornamental or fanciful designs cast integral with the plate, the grain of the central piece being across the 55 grain of the outer pieces, substantially as described.

3. A sign consisting of a wooden body, A, formed of a central piece having rounded edges a', and outer pieces having edges a'' 60 rounded toward the edges of the central piece, and plates C C, each plate having ornamental or fanciful designs cast integral with the plate, substantially as set forth.

CHARLES O. BAXTER.

In presence of—

GEO. H. KNIGHT,
JOSEPH WAHLE.
